UNITED STATES PATENT OFFICE.

JOSEPH DODDS, OF GLASGOW, SCOTLAND.

ROTARY TIPPLER FOR USE IN DISCHARGING COAL OR OTHER MINERAL FROM HUTCHES, CORVES, OR THE LIKE.

1,020,133.

Specification of Letters Patent. Patented Mar. 12, 1912.

Application filed June 20, 1911. Serial No. 634,197.

To all whom it may concern:

Be it known that I, JOSEPH Dodds, a subject of the King of Great Britain, residing at Rutherglen, Glasgow, Scotland, have invented certain new and useful Improvements in Rotary Tipplers for Use in Discharging Coal or other Mineral from Hutches, Corves, or the Like, of which the following is a specification.

10 This invention relates to rotary tipplers or tipples for use in discharging coal or other mineral from the hutes, corves or such like within which it is conveyed.

15 The object of my present invention is to provide a rotary tippler wherein the necessity for employing the usual creeper or drag for drawing the hutes is obviated and wherein the discharging and righting operations are automatically and rapidly performed.

Under this invention the hutes are turned downward through a half revolution so as to discharge their contents and are thereafter raised upward through a second 25 half revolution in such manner as to again right them and at the same time bring them to a level higher than their level on entering the tippler, the power for raising the empty hutes to the higher level being 30 obtained from the loaded hutes and the coal discharged therefrom.

In order that the invention may be clearly understood, I have hereunto appended explanatory drawings which show, by way of 35 illustration or example, one mode of carrying out the invention.

On the said drawings:—Figure 1 is a side elevation of the rotary tippler. Fig. 2 is an end view thereof.

40 The rotary tippler shown on the drawings is made in two parts, a discharging device *a* and a righting device *b*, the loaded hutes *c* entering the discharging device from the inclined rails *d* while the empty hutes *c* 45 pass from the righting device to the inclined rails *d*.

The discharging device is made with a horizontal shaft 1 mounted in bearings 2 and having secured thereon a rectangular 50 frame 3 upon which are mounted four sets of rails 4, each rail being made double, as usual in rotary tipplers, so as to provide a running surface for the wheels while 7 for limiting the movement of the rails 4 55 is hinged, at 5, to the said frame 3 at the

entrance end of the discharger and, at the exit end of the same, there is provided, on the frame 3, a projection 6 having a head 7 for limiting the movement of the rails 4 outward from the shaft 1. Secured to each 60 set of rails 4 is an inclined plate 8 of rectangular form or the equivalent thereof, and suitably mounted at the side of the discharging device is a stationary chute 9 of channel formation having its upper part 65 curved to conform to the circle described by the plates 8 which project thereinto while the lower part of the chute is so formed as to direct downward the coal supplied thereto from the hutes being discharged. The 70 shaft 1 of the discharging device has secured thereon, at the entrance end of the device, a brake wheel 10 adapted to be engaged by a friction band 11 which may be tightened on the wheel by means of a hand lever 12, 75 and located between the ends of the rails *d* is a sliding bolt 13 which may be moved by means of a hand lever 14 into or out of the path of a number of projections 15 provided on the end of the frame 3, one adjacent to 80 each set of rails 4, so that, when the bolt 13 is in its operative position, the discharger is held with a set of rails 4 in position to receive a hutch from the rails *d*. The sets of rails in the upper part of the discharger 85 lie axially of the shaft 1 and as they move to the bottom of the discharger they turn on their hinges 5, the exit ends being stopped by the heads 7 so that the rails 4 lie at an angle and the hutes *c* may run 90 therefrom by gravity. The righting device *b* receives the inverted and discharged hutes which run from the discharging device.

The righting device *b*, which is arranged 95 in line with the discharging device *a*, consists of a horizontal shaft 16 mounted in bearing brackets 17, and driven by means of a gear wheel 18 thereon from a gear wheel 19 on the shaft 1 of the discharging device, and secured on the shaft 16 between the brackets 17 is a frame 20 carrying four sets of rails 21 arranged at a slight angle to the shaft 16, in such manner that the hutch *c*, carried in the set of rails for the time being lowermost, may run therefrom over bridge rails 22 mounted upon pedestals 23 and into the set of rails for the time being lowermost in the righting device 100 while the discharged and righted hutch for 110

the time being uppermost in the righting device may run therefrom on to the rails d^1 . Suitable means may be provided for preventing a loaded hutch leaving the rails d before a set of rails is in position to receive the same, and means are provided for preventing a hutch from leaving the discharging device before it has reached the lowermost position or from leaving the righting device before it has reached the uppermost position.

In operation, the attendant withdraws the bolt 13 from the path of the projections 15 by means of the hand lever 14 and operates the brake lever 12 so as to release the shaft 1 and the discharging device is caused to rotate in the direction of the arrow, Fig. 2, by the weight of the loaded hutches in the discharger. As the device rotates the contents of the hutches are discharged on to the plates 8 in the chute 9 and, by acting on the plates assist in the rotation of the device, and as each discharged hutch reaches the lowermost position in the discharging device the rotary motion is stopped by means of one of the projections 15 which engages the bolt 13. Each time the rotary motion is arrested in this manner a loaded hutch is run on to the uppermost rails 4 and at the same time the lowermost rails 4 turn on their hinges 5 and take up an inclined position while the inverted and discharged hutch thereon runs down on to the lowermost set of rails 21 in the rotary righting device b . The rotary motion of the discharger a being transmitted to the righter b through the gear 18, 19, the discharge hutches on being received by the righting device at the bottom thereof are raised upward in a semi-circular path while being righted and as they reach the uppermost position in the righting device they are permitted to run from the rails 21 on to the inclined railway d^1 the operation being thus automatically continued, a loaded hutch being supplied to the tippler and an empty hutch being supplied therefrom at each quarter of a revolution made by the tippler.

The device a may itself be used as a discharging and righting device, the hutches in this case being caused to make a complete revolution therein. As each empty hutch comes to the top it is removed and its place taken by a loaded hutch.

Having now fully described my invention what I claim and desire to secure by Letters Patent is:—

1. A rotary tippler comprising, in combination, a discharging device in which the hutches are turned downward so as to discharge the contents, and a righting device which is adapted to receive the discharged hutches and raise the same to a level higher than the level of entry of the loaded hutches into the discharging device.

2. A rotary tippler comprising, in combination, a discharging device in which the hutches are turned downward so as to discharge their contents, a righting device which is adapted to receive the discharged hutches and raise the same to a level higher than the level of entry of the loaded hutches into the discharging device and means for operating the righting device simultaneously with the discharging device. 75

3. A rotary tippler comprising, in combination, a discharging device in which the hutches are turned downward through a half revolution so as to discharge the contents and a righting device which is operated automatically from the discharging device and is adapted to receive the discharged hutches and raise the same to a level higher than the level of entry of the loaded hutches into the discharging device. 80

4. A rotary tippler comprising, in combination, a discharging device in which the hutches are turned downward through a half revolution so as to discharge the contents, a righting device which is adapted to receive the discharged hutches and raise the same to a level higher than the level of entry of the loaded hutches into the discharging device, and means whereby the righting device is operated automatically from, and 90 simultaneously with, the discharging device.

5. A rotary tippler comprising, in combination, a discharging device, means in the discharging device for receiving the loaded hutches, means on the discharging device 100 whereby the mineral discharged and the loaded hutches together cause the device to rotate and discharge the said mineral from the hutches, a righting device which is adapted to receive the discharged hutches 105 and raise the same to a level higher than the level of entry of the loaded hutches into the discharging device, and gearing whereby the righting device is operated automatically from the discharging device. 110

6. A rotary tippler comprising, in combination, a rotary discharging device, a series of sets of rails in the said device and adapted to receive the hutches, means whereby the device is rotated by the loaded hutches and the mineral discharged therefrom, a righting device, a series of sets of rails in the righting device and adapted to receive the discharged hutches from the discharging device, and means for automatically rotating the righting device from the discharging device in such manner as to raise the hutches to a level higher than the level of entry of the loaded hutches into the discharging device. 115

7. A rotary tippler comprising, in combination, a rotary discharging device, a series of sets of rails in the said device and adapted to receive the hutches, means whereby the device is rotated by the loaded 120

125

130

hutches and the mineral discharged therefrom, a central horizontal shaft in the discharging device, a righting device, a series of sets of rails in the righting device and 5 adapted to receive the discharged hutes from the discharging device, a central horizontal shaft in the righting device, and gear wheels on the said central horizontal shafts for automatically rotating the righting device from the discharging device in such manner as to raise the hutes to a level higher than the level of entry of the loaded hutes into the discharging device.

8. A rotary tippler comprising, in combination, a rotary discharging device, a series of sets of rails in the said device and adapted to receive the hutes, an inclined plate adjacent each set of rails and adapted to receive the mineral discharged from the 15 hutes and so assist in the rotation of the device, a stationary chute adapted to prevent the escape of the mineral from the said plates, a central horizontal shaft in the discharging device, a righting device, a series 20 of sets of rails in the righting device and adapted to receive the discharged hutes from the discharging device, a central horizontal shaft in the righting device and gear 25 wheels on the said central horizontal shafts for automatically rotating the righting device from the discharging device in such manner as to raise the hutes to a level higher than the level of entry of the loaded hutes into the discharging device.

35. 9. A rotary tippler comprising, in combination, a rotary discharging device, a series of sets of rails in the said device and adapted to receive the hutes, an inclined plate arranged adjacent each set of rails 40 and adapted to receive the mineral discharged from the hutes and so assist in the rotation of the device, a stationary

curved chute adapted to receive the plates and prevent the escape of the mineral therefrom, a righting device, means whereby the 45 sets of rails in the righting device can incline so as to allow the discharged hutch to run therefrom, a series of sets of rails in the righting device and adapted to receive the discharged hutes from the discharging 50 device, and means for automatically rotating the righting device from the discharging device in such manner as to raise the hutes to a level higher than the level of entry of the loaded hutes into the discharging device.

10. A rotary tippler comprising, in combination, a rotary discharging device, a series of sets of rails in the said device and adapted to receive the hutes, means whereby the device is rotated by the loaded hutes and the mineral discharged therefrom, a righting device, a series of sets of rails in the righting device and adapted to receive the discharged hutes from the discharging device, means for automatically rotating the righting device from the discharging device in such manner as to raise the hutes to a level higher than the level of entry of the loaded hutes into the discharging device, means for supplying the loaded hutes to the discharging device, means for conveying the discharged hutes to the righting device, means for receiving the righted hutes from the righting device and means for controlling the operation of the tippler.

In testimony whereof I affix my signature in presence of two witnesses.

JOSEPH DODDS.
